UNITED STATES PATENT OFFICE.

EARL L. CRABB, OF INDIANAPOLIS, INDIANA.

COMBINED PICTURE-EXHIBITOR AND PHONOGRAPh.

No. 833,508.

Specification of Letters Patent.

Patented Oct. 16, 1906.

Application filed July 21, 1905. Serial No. 270,608.

To all whom it may concern:

Be it known that I, EARL L. CRABB, a citizen of the United States, residing at Indianapolis, in the county of Marion and State of Indiana, have invented new and useful Improvements in a Combined Picture-Exhibitor and Phonograph; and I do declare the following to be a full, clear, and exact description of the invention, reference being had to the accompanying drawings, and to the letters and figures of reference marked thereon, which form a part of this specification.

This invention relates to coin-controlled repeating phonographs and apparatus connected therewith and operated thereby for exhibiting or displaying pictures, more particularly series of pictures illustrating the subject-matter of the phonograph-records while being transmitted to the listeners, the invention having particular reference to the exhibitor mechanism whereby the pictures may be moved into position for observation in succession, the invention having reference also to the apparatus for holding and carrying the pictures.

Objects of the invention are to provide simple and relatively cheap apparatus of the above-mentioned character and means for economically operating the apparatus by means of the phonograph mechanism so as to obviate the necessity of providing an independent or separate motor for the picture-exhibitor and to provide inexpensive means for holding and carrying the pictures.

The invention consists in the application to the mechanism of a coin-controlled repeating phonograph, of apparatus that is driven by the phonograph when in operation continuously and moving the pictures, stop devices for periodically arresting the movements of the pictures, and means for connecting the pictures operatively with the apparatus; and the invention consists, further, in the novel parts and the combinations and arrangements of parts, as hereinafter particularly described and claimed.

Referring to the drawings, Figure 1 is a vertical sectional view of a phonograph-cabinet partially broken away and a front elevation of the phonograph having the improved picture-exhibitor connected therewith; Fig. 2, a horizontal sectional view of the cabinet, taken above the phonograph and exhibitor,

the instruments in the cabinet being shown in a top plan view; Fig. 3, a fragmentary 55 vertical sectional view on the line A A in Fig. 2; Fig. 4, a fragmentary vertical sectional view of the cabinet and an end elevation of the phonograph and exhibitor in the cabinet; Fig. 5, a fragmentary vertical sectional view 60 on the line B B in Fig. 2. Fig. 6 is a fragmentary transverse sectional view of the phonograph near the head end of the mandrel, showing the repeating attachments connected therewith, the reproducer being elevated 65 above the record, as when returning; Fig. 7, a fragmentary top plan showing the position of the reproducer after having traversed the record and at rest; Fig. 8, a fragmentary 70 front elevation showing parts of the phonograph and repeating attachment; Fig. 9, a rear elevation of the parts of the repeating attachment that operate to lift the reproducer, so that it may return to repeat; Fig. 10, an end elevation of the attachments 75 shown in the preceding figure, and Fig. 11 a fragmentary sectional view of the head of the reproducer-arm in which the guide-pin is slidingly mounted.

Similar reference characters in the several 80 figures of the drawings designate corresponding elements or features.

In practically carrying out the invention new phonographs may be provided or well-known phonographs may be obtained in the 85 market that may be altered to suit the purposes of the present invention, and in either case novel repeating attachments may be applied to the phonographs adapted to be coin-controlled. For the purposes of describing the present invention a well-known 90 type of phonograph is illustrated that is driven by a spring-motor and mounted in a cabinet, the instrument being provided with peculiar repeating attachments that are the 95 subject-matter of Patent No. 794,786, dated July 18, 1905, and patent application, Serial No. 267,338, filed June 28, 1905, and need not be described herein in detail.

In the drawings, *a* designates the body of a 100 suitable cabinet; *b*, the top, and *c* the front door, of the cabinet; *d*, a suitable platform supported in the cabinet and having the base *e* of the upper works of the phonograph mounted thereon, the principal upper works 105 comprising well-known elements—such as

the mandrel *f*, the record *g*, the reproducer-arm guide-bar *h*, the feed-screw *i*, the reproducer-arm *j*, the feed-nut *k*, the buffer-stop *l*, the reproducer-head *m*, the ear-tube *n*, the 5 guide-head *p* of the reproducer-head, and the reproducer guide-bar *q*.

The phonograph includes an attachment comprising a cord *r*, connected with the reproducer-head and running over a suitably-

- 10 supported guide-sheave *s*, and a weight 6 attached to the cord for returning the reproducer in order to repeat the record. In the guide-head *p* is a longitudinally-movable guide-pin *C*, that may be pushed inwardly 15 upon the guide-bar *q* for holding the reproducer away from the record while returning to the starting-point. Another attachment is connected with the phonograph for elevating the reproducer and pushing the guide-
- 20 pin *C* onto the guide-bar *q*, and it comprises a movable arm *D*, spring-pressed upwardly and supported on a stand *E*, that is suitably mounted on the platform *d*, the stand also supporting pin-guides *F*, *G*, and *H*, and the 25 guide-pin *C* operates in connection with the guides and the arm in its various movements for placing the pin onto the guide-bar *q* when carried by the guide-head *p*. A latch *J* is mounted on the stand for holding the de-
- 30 pressed arm *D* and has an operating-lever *t*, that extends under a coin-chute *u*, that is attached to the top *a* of the cabinet, there being a hopper 7 below the chute to receive the coins that may be used to actuate the latch.

- 35 The phonograph-motor is mounted against the under side of the platform *d*, the construction of the motor being well-known, *v* indicating the frame thereof, *w* the brake-wheel, and *x* the spring-retracted brake-lever, 40 which is provided with a reach-rod *y*, that extends along the guide-bar *q*, so as to be engaged by the guide-head *p* when the reproducer reaches the end of the record to stop the motor, a key *z* being used for winding the 45 motor-spring. The motor has a driving-shaft *K*, on which is a pulley 8, to which is connected a belt 9, that turns the mandrel *f*.

- In the present invention a pair of standards *L* and *L'* are mounted on the platform *d* 50 and project forwardly and upwardly beyond the front thereof; but the standards may be otherwise supported. A pair of picture-guides *M* and *M'* are attached to the standards and have each an inclined guide-face 10.
- 55 A cylindrical driving-shaft *N* is rotatively mounted in the standards above the guides, and it is provided with a drive-pulley 11, about which extends a drive-belt 12, that extends also about a drive-pulley *O*, with which the 60 shaft *K* has been provided in practically carrying out the present invention.

A pair of endless belts *P* and *P'* are hung on or extend over the shaft *N* to be driven

thereby and support a roller *Q* for stretching the belts, which may be of any suitable 65 lengths. A series of picture-cards, as *R* *R'* *R''* *R'''* *R''''*, are secured to the outer sides of the belts *P* and *P'* by suitable means, as staples *S*, or by other means permitting of the cards being detached from the belts, if 70 desired. Each card has a finger *T* attached to its upper edge, each finger being in a different position relatively to the other fingers on the different cards, as shown. An arm *U* is secured to the guide-head *p* and extends forwardly, so as to have its end in the path of the fingers *T* when they are carried by the 75 cards in their movements over the shaft *N*. A stereoscope *V* is mounted on the top *b* of the cabinet above the drive-shaft *N*. 80

In practical use if the machine be put in operation with the reproducer at the beginning of the record the driving-shaft *N* will revolve continuously, being driven by the shaft *K* of the phonograph-motor. The picture-card that has a finger *T* in the proper position to engage the arm *U* will be carried to the top of the shaft *N* and will be held in an approximately horizontal position by reason of the finger engaging the arm, whereby 90 the belts *P* and *P'* will be prevented from moving with the shaft *N*, the shaft slipping against the belts or under them. As the record is traversed by the reproducer its arm moves the arm *U*, which will pass from beneath the finger *T*, and thus release the card, so that the following card will be carried upon the shaft *N*, and the finger of the second card will engage the arm *U*, thereby stopping the belts *P* and *P'* and the picture-cards, and so on each card will be brought in succession into view and stopped opposite the stereoscope *V* until when the last one of the series is in view the advanced pin *C* will ride on the movable arm *D* under the horizontal 105 guide *F*, and thus depress the arm *D*, which will be held down by the latch *J*, the rod *y* being engaged by the guide-head *p*, so as to apply the brake and stop the machine when the record has been completed or rendered in 110 full, the whole apparatus being now ready for another operation or repetition of the previous record and accompanying exhibition of the pictures. If now a coin be placed in the coin-chute *u*, it will fall upon the lever *t* of the latch *J* and thence into the hopper 7, a suitable bin being usually provided to receive the coins from the hopper. The force of the falling coin will move the latch *J* so as to release the arm *D*, which will engage the pin *C* 115 and lift it high enough to permit of its being carried by the weight 6 and connections onto the inclined guide *G*, from which it will be pushed by the guide *H* onto the guide-bar *q*, and as the reproducer rises as a result of the 120 pin riding on the guide *G* the brake is re- 125

- leased, as is the feed-nut, so that the reproducer will be returned with the pin upon the guide-bar *q* by means of the weight 6. When the inner end of the pin *C* while moved by the returning reproducer-arm engages the inclined guide *I*, with which the guide-bar *q* is provided, the pin will be forced from the guide-bar and allow the reproducer to descend into contact with the record. The return operations will be rapid, so that the arm *U* will engage the finger *T* of the first picture-card of the series as it approaches. The above-described operations will then be repeated. When the records are changed, the pictures also will be changed, and the picture-cards that may not be in use may be compactly folded, so that each series will be conveniently held together ready for use in regular order.
- Having thus described the invention, what is claimed as new is—
1. A picture-exhibitor including an endless belt, a plurality of cards mounted on the belt to be moved thereby and provided with projections arranged at relatively different points on the different cards.
  2. A picture-exhibitor including a driving-shaft, an endless belt hung on the driving-shaft to be moved thereby, a plurality of exhibition-cards attached intermediately of their top and bottom ends to the belt and provided each with a projection arranged at a point relatively different to those of the remaining ones of the plurality of cards, and a stop device movable successively into engagement with the projections of the plurality of cards.
  3. Displaying apparatus including a rotative driving-shaft, an endless belt hung on the shaft to be moved thereby and permitting the shaft to periodically move relatively thereto, a plurality of exhibition-cards mounted on the belt and movable thereby, a movable stop device, and a motor connected with the driving-shaft and also with the stop device operating to force the stop device to arrest the belt periodically, the motor also operating to rotate the shaft while the movement of the belt is arrested.
  4. A combined picture-exhibitor and phonograph including a rotative driving-shaft, a rotative phonograph-record mandrel, a motor operatively connected with the driving-shaft and also with the record-mandrel, a belt extending about the driving-shaft to be driven thereby, a plurality of picture-cards mounted on the belt, and means for arresting the motion of the belt intermittently while the driving-shaft and the record-mandrel continue in motion.
  5. A combined picture-exhibitor and phonograph including a rotative driving-shaft, a rotative phonograph-record mandrel, a motor connected with the driving-shaft and also with the record-mandrel, a plurality of belts extending about the driving-shaft to be driven thereby, a plurality of picture-cards mounted on the belts and provided each with a projecting finger, and movable means for engaging the fingers of the picture-cards successively and intermittently arresting the motion of the belts while the driving-shaft and the record-mandrel continue in motion.
  6. A combined picture-exhibitor and phonograph including a rotative driving-shaft, a rotative phonograph-record mandrel supporting a record, a movable reproducer-arm, a motor connected with the driving-shaft and the record-mandrel, a plurality of belts mounted on the driving-shaft to be driven thereby, a plurality of picture-cards mounted on the belts, and an arm supported by the reproducer-arm for intermittently arresting the movements of the picture-cards while the driving-shaft and the record continue in motion.
  7. A picture-exhibitor including a rotative shaft, supports for the shaft, a plurality of exhibition-cards provided collectively with a carrying-belt to be driven by the rotative shaft and having fingers attached thereto at different distances on the different cards from the ends thereof, motive means for driving the rotative shaft, and an arm movable by the motive means for engaging the fingers successively to arrest the movements of the cards.
  8. A picture-exhibitor including a plurality of cards having projecting fingers, a plurality of belts attached to the cards enabling the cards to be folded together serially, a rotative shaft whereon the belts may be hung and moved, a motor, an arm movable by the motor, and a drive-belt connecting the rotative shaft with the motor for moving the cards and drawing the fingers thereof in succession into the path of the arm to be arrested and released thereby.
  9. A combined picture-exhibitor and phonograph including a rotative driving-shaft, a rotative phonograph-record, a motor driving the shaft and the record, a belt mounted on the driving-shaft and having exhibiting-cards mounted thereon provided with projections, means for engaging the projections of the cards successively and arresting the movements of the cards, automatic means for periodically stopping the phonograph-record and driving-shaft, and means for releasing the automatic means from action.
  10. In displaying apparatus, the combination of a rotative shaft, a plurality of endless belts hung on the shaft to be driven thereby and permitting rotation of the shaft in slipping contact therewith, a plurality of display-

cards mounted on the belts, a motor for rotating the shaft continuously, movable means for intermittently stopping the belts, and means for controlling the movable means in its actions.

11. In displaying apparatus, a plurality of cards having each a projection, a tape-like flexible fabric belt attached to the cards enabling the cards to be folded together; a rota-

tive shaft for supporting and moving the belt, and a movable stop device for engaging the projections of the cards.

In testimony whereof I affix my signature in presence of two witnesses.

EARL L. CRABB.
